UNITED STATES PATENT OFFICE.

EDWARD C. DANIELSON, OF STURGEON LAKE, MINNESOTA.

DRAINING DEVICE.

1,366,250.

Specification of Letters Patent. Patented Jan. 18, 1921.

Application filed April 22, 1919. Serial No. 291,911.

To all whom it may concern:

Be it known that I, EDWARD C. DANIELSON, a citizen of the United States, residing at Sturgeon Lake, in the county of Pine and State of Minnesota, have invented certain new and useful Improvements in Draining Devices; and I do hereby declare the following to be a full, clear, and exact description of the invention, such as will enable others skilled in the art to which it appertains to make and use the same.

This invention relates to draining devices, and more particularly to a device adapted for use in connection with well pumps.

One of the main objects of the invention is to provide a device of the character stated of simple construction and operation which may be readily applied to a pump of standard construction and may be easily operated from the pump platform for draining water from the water pipe or standard so as to prevent freezing of the pump. A further object is to provide simple and efficient means which may be produced at relatively small cost and may be readily applied without necessitating changes in the pump structure. Further objects will appear from the detailed description.

In the drawings:

Figure 1 is a side view of a pump of conventional construction and the pipe or standard associated therewith showing a device constructed in accordance with my invention applied.

Fig. 2 is a central vertical section through the device and the contiguous portion of the pump standard.

Fig. 3 is a top plan view of the device.

The draining device designated generally by 1 is formed of two sections 2 and 3 which are adapted to be secured tightly about pipe standard 4 depending from pump 5 of any suitable type.

Section 3 is provided with a cylindrical bore 6 extending from the upper end thereof, the lower portion of this bore being reduced and of inverted conical shape, as at 7, to snugly receive a correspondingly shaped valve 8 having a reduced stem 9 extending through bore 6 axially thereof, the upper end of this stem projecting above the upper end of member 3. The valve is normally held in depressed or seated position by an expansion coil spring 10 mounted about valve stem 9, this spring being confined between a metallic washer 11 resting

upon a leather washer 12 seated upon the upper end of valve 8, and a washer 13 secured in the upper end of bore 6. The upper end portion of valve stem 9 is reduced, as at 9^a, to form a shoulder 9^b adapted to engage washer 13 for positively limiting upward movement of the valve so as to prevent injury to spring 10. The leather washer 12 is adapted to fit snugly the interior of bore 6 so as to prevent leakage of water into the upper portion of the bore and consequent corrosion of the spring.

Member 3 is provided with a water receiving duct 14 communicating with the lower reduced portion 7 of bore 6 a short distance above the lower end thereof, this duct being in register with a drainage opening 15 provided through the pipe standard 4. Member 3 is further provided with a water discharge duct 16 extending from the lower end thereof and communicating with the lower end of the reduced portion 7 of bore 6. An operating rod 17 is secured to the upper end of valve stem 9 and extends through pump platform 18, this rod providing means whereby the valve may be readily raised so as to permit water to drain out of pipe 4. A suitable cover plate 19 is preferably, though not necessarily, provided for the drainage device 1, this cover plate acting to effectually prevent spreading apart of the upper ends of members 2 and 3 while also providing a guide for reciprocation of valve stem 9.

In practice, the drainage device will be placed from ten to twenty feet below the pump platform, depending upon the depth of the well and the length of the pipe standard 4. Normally the valve 8 will be held in depressed or seated position so that the water column in pipe 4 will be maintained thus avoiding all necessity for priming the pump. In cold weather when there is danger of the water in the pipe freezing, the valve may be raised so as to permit the water to readily drain from the pipe standard from above the cylinder thus eliminating freezing of this water. In this case, also, the draining of the water from the standard will not necessitate priming of the pump such as is necessary where the water is drained from the pump cylinder, as is a common practice. As will be appreciated, this device may be readily applied to a pump pipe standard without necessitating any changes in the construction of the

standard and it is, therefore, very practical and efficient. Also, while the device has been illustrated and described as used in connection with a pipe standard for a pump, 5 it will be understood that it may be equally well applied to any pipe in which a water column is formed, such as a pipe for supplying water to a storage tank, or for similar purposes.

10 While I have illustrated and described the preferred form of my invention it will be evident that, in practice, it may be desirable to resort to slight changes in the construction and arrangement of the details 15 of the invention, and I intend to include all such variations, as fall within the scope of the appended claim, in this application in which a preferred form only of my invention is disclosed.

20 What I claim is:

In combination with a pipe standard provided at its side with an opening, a draining device comprising sections adapted to be applied to the sides of the standard, 25 means for clamping the sections in position upon the standard, one of the sections being provided with a longitudinally disposed bore and a longitudinally disposed counter-

bore, the bore and counter-bore being in alignment with each other, the said section 30 being further provided with an opening which is adapted to communicate with the opening in the standard and which communicates at its inner end with the counter-bore in the section, a plate applied to 35 the last mentioned section, and closing the upper end of the counter-bore and secured to the other section, a valve slidably mounted in the counter-bore and fitting snugly therein and adapted to move across the 40 opening which lead into the counter-bore and adapted close against the end of the bore, and a spring located in the counter-bore and bearing at one end against the fixed abutment and at its other end against 45 the said valve and being under tension with a tendency to normally hold the valve in position across the opening which communicates with the counter-bore.

In testimony whereof I affix my signature 50 in presence of two witnesses.

EDWARD C. DANIELSON.

Witnesses:

CHRISTINE DANIELSON,
E. B. LINSLEY.
